UNITED STATES PATENT OFFICE.

CHARLES PARTINGTON, OF CINCINNATI, OHIO.

SWITCH-STAND.

SPECIFICATION forming part of Letters Patent No. 536,890, dated April 2, 1895.

Application filed September 17, 1894. Serial No. 523,274. (No model.)

To all whom it may concern:

Be it known that I, CHARLES PARTINGTON, residing at Cincinnati, in the county of Hamilton and State of Ohio, have invented certain new and useful Improvements in Switch-Stands, of which the following is a specification.

The object of my invention is to provide an automatic spring switch stand to be of simple construction and easy of operation.

The various features of my invention will be more fully set forth in the description of the accompanying drawings making a part of this specification, in which—

15 Figure 1, is a side elevation with the operative parts shown in section. Fig. 2, is a sectional elevation of the operative parts shown in Fig. 1, on their center line of movement. Fig. 3, is a top view partly in plan and partly 20 in section. Fig. 4, is a section on line x , x , Fig. 1.

A represents the base of the stand; B, the frame thereof.

C represents a crank shaft which journals 25 in the brackets a , a .

The top of the frame is enlarged and is provided with housing D. This housing is provided with two pockets b , b , in which are placed tension springs c .

30 E represents a wedge-shaped recess between the pockets which inclose the springs.

d represents a yoke which is attached to the spring rods e , e . These rods pass through the ears of the yoke d and are secured by 35 nuts. The springs seat at one end against the ends of the pockets and at the opposite ends against the collars i .

F represents a link hinged at one end to the yoke d and at the opposite end to the link G.

40 H represents a cap piece provided with a gain or way in which link G slides. It is pinned to the crank shaft and provided with a mortise I in which the knee lever K is pivoted.

45 L represents a target shaft in the socket of the cap piece.

In Fig. 1, the lever is shown in an elevated position for turning the crank shaft and throwing the switch with the strains of the springs removed.

50 When the lever is fastened down in the position shown in Fig. 3, the links cannot be moved into the position shown in Fig. 2, without compressing the springs and this is done automatically by the train, the switch in this 55 position being locked against ordinary hand movement.

By the construction herein shown many important advantages are obtained. The links F, G, are housed, and the link F moves freely 60 on its two pivots, link F sliding freely in the gain of the cap piece. By employing two springs instead of one, smaller springs can be employed and by placing them in the pockets the springs can be readily adjusted to any 65 desired tension. The parts are of very simple construction and are very durable.

I claim—

1. In an automatic switch stand the combination of the links F, G, and yoke d and 70 springs c , attached to the yoke, substantially as specified.

2. In an automatic switch-stand, the combination with a frame provided with a housing having a wedge-shaped recess, of springs c in- 75 closed in the housing, a link F moving in the said wedge-shaped recess, a yoke d to which one end of the link is pivoted, and a link G to which the opposite end of the link is piv- 80 otally connected, substantially as and for the purposes described.

3. In an automatic switch stand the combination of the frame B, crank shaft C, cap piece H, housing D, springs c , yoke d , and links F, G, and lever K, substantially as specified. 85

In testimony whereof I have hereunto set my hand.

CHARLES PARTINGTON.
